JOHN C. RINGE, OF STRATFORD, CONNECTICUT, ASSIGNOR TO THE SINGER MANUFACTURING COMPANY, OF ELIZABETH, NEW JERSEY, A CORPORATION OF NEW JERSEY.

NEEDLE GUARD FOR SEWING MACHINES.

Application filed April 30, 1921. Serial No. 465,720.

To all whom it may concern:

Be it known that I, JOHN C. RINGE, a citizen of the United States, residing at Stratford, in the county of Fairfield and State of Connecticut, have invented certain new and useful Improvements in Needle Guards for Sewing Machines, of which the following is a specification, reference being had therein to the accompanying drawings.

10 This invention relates to improvements in needle- and needle-thread loop guarding devices particularly adapted for use in connection with sewing machines in which the needle moves laterally in and relatively to 15 the material being operated upon, as in hemstitching machines.

Lateral movements toward the loop-taker of the needle while in the material have a constant tendency to bend or deflect the 20 needle, rendering uncertain the seizure of the needle-thread loop by the loop-taker. This is especially true when operating upon very 25 closely woven and wiry materials. There is furthermore a tendency, particularly when operating at high speed to throw out the needle-thread in the opposite direction from its lateral movement, thereby robbing the 30 needle-thread loop to be entered by the loop-taker on the other side of the needle. This naturally has also a tendency to occasion skipping of stitches.

The present invention has for its primary object to obviate these difficulties by the provision of a guarding device functioning to 35 properly position the needle with respect to the loop-taker and also to back up the needle to prevent the throwing out of a needle-thread loop on the wrong side of the needle.

The invention has also for its object to 40 provide a guarding device for the purpose referred to permitting adjustment of the lateral throw of the needle i. e., of the width of the hemstitch figure.

The invention has for a further object to 45 provide a guarding device of this character with means permitting adjustment of the path of movement of the guarding device.

Other objects of the invention will be 50 apparent from the following description and claims.

In one embodiment of this invention, the present improvement has been applied to a hemstitching machine in which the needle is reciprocated endwise and actuated laterally

by well known means to penetrate the material on and off the hem-fold. The feeding mechanism of the machine, as usual, includes a feed-dog to which are imparted two forward feeding movements and one backward feeding movement in the formation of each hemstitch figure. As is well known, the needle is caused by its actuating mechanism to penetrate the hem-fold of the material immediately following the first forward feeding movement of the feed-dog, descending below the work to throw out a loop in proper position for seizure by the supplemental loop-taker. The needle then rises and the second forward feeding movement of the feed-dog occurs, while the needle is moved laterally to penetrate the material off the hem-fold. During its penetrating movement i. e., while in the material, it is again moved laterally in the opposite direction to draw the threads of the fabric and at the same time to bring the needle-eye into proper position with respect to the loop-taker beak to form the stitch. The needle then rises and a backward movement of the feed-dog occurs while the needle is again moved laterally to penetrate the material off the hem-fold, whereupon a like action occurs while in the material.

It will be seen that in order to provide a needle-guard for a needle of this character, it is essential that the guard be out of the way of the needle when penetrating the material off the hem-fold and nevertheless catch up with the needle moving laterally in the material so as to back up the thread to insure the formation of the loop on the loop-taker side of the needle and also to insure proper positioning of the needle-eye with respect to the loop-taker beak.

To this end the present embodiment of the invention comprehends, in a hemstitching machine, a needle-guard fulcrumed intermediate its ends and actuated from an eccentric on the loop-taker shaft. The fulcrum for the needle-guard is in the form of a stud eccentrically secured so as to permit adjustment of the path of movement of the needle-guard, while the throw of the guard is preferably such as to permit of a slight adjustment of the lateral throw of the needle.

In the accompanying drawings, Fig. 1 is a view in elevation and partly in section of the front side of a hemstitching machine em-

bodying the present improvement. Fig. 2 is a front end elevation of the same. Fig. 3 is a perspective view of the needle-guard, its supporting stud and its actuating means. 5 Figs. 4, 5 and 6 illustrate progressive positions of the needle and needle-guard while the point of the needle is below the throat-plate.

Referring to the drawings, the hemstitching machine in which the present improvement has been embodied is shown as constructed with a base 1 from which rises a hollow standard 2 curving into an overhanging arm 3 terminating in a head 4. Mounted for vertical movements in suitable bearings provided in the head 4 is the usual presser-bar 5 carrying the presser-feet, as 6. Journaled in the overhanging arm is the main-shaft 7, carrying at one end the belt-pulley 8 and at its other end suitably connected by means of shaft-flange 9 and link 10 with the needle-bar 11 journaled for vertical reciprocation in the head 4. Secured by means of the screw 12 to the lower end 15 of the needle-bar is the bracket 13, carrying the piercer 14 and upon which is fulcrumed, by means of the screw 15, the needle-carrying clamp 16. The needle-carrying clamp 16 is suitably socketed for the reception of 20 the shank of the needle 17 secured therein by means of a set-screw 18. Secured in the needle-clamp 16 by means of the set-screw 19 and projecting upwardly therefrom is the needle-vibrating rod 20 of which the upper end 25 is slidingly mounted in the swivel-joint 21 carried by a vibratory guide-bar 22 supported at its upper end for swinging movements upon a pivot-screw 23 threaded into the block 24 affording an upper bearing for the needle-bar. To steady the 30 swinging movements of the guide-bar 22 the lower end thereof is provided with a guiding fin 25 entering a notch in the block 26 affording a lower bearing for the needle-bar. 35

Intermediate its ends the guide-bar 22 is suitably connected with one end of a needle-vibrating connection 27 of which the opposite end is suitably connected with the depending end of an arm 28 adjustably secured by means of the screw 29 in a suitable slideway provided in the radial-arm 30, fulcrumed upon the machine-frame and deriving vibratory movements from the usual 40 cam 31 secured upon the secondary shaft 32. The secondary shaft 32 is suitably journaled in the machine-frame and carries a gear 33 in mesh with a pinion 34 secured upon the main-shaft 7. It will be apparent 45 that rotation of the main-shaft 7 will, through the described connections, impart lateral movements to the needle and these movements, as is usual in hemstitch machines, cause the needle to reciprocate once 50 in a straight path and then twice while lat-

eral movements are imparted thereto both in and out of the material for each hemstitch figure.

The feeding mechanism comprises a feed-dog 35 operating through suitable slots 36 provided in the throat-plate 37 and is carried by the feed-bar 38 actuated in any suitable manner, one form of which actuating mechanism is disclosed and described in the U. S. patent to C. M. Abercrombie, No. 1,271,256, of July 2, 1918. As feeding mechanisms of this character are well known in the art and as the particular form employed is unimportant to the present invention, it is deemed unessential to herein describe such a mechanism for a complete understanding of the present improvement. 75

Carried by the main-shaft 7 is the belt-pulley 39 connected by means of the belt 40 with the pulley 41 suitably secured upon the loop-taker actuating shaft 42. The loop-taker actuating shaft 42 is suitably journaled beneath the cloth-plate 43 and carries the bevel-gear 44 in mesh with a similar gear 45 suitably secured upon the loop-taker shaft 46 carrying the loop-taker 47, the shafts 42, 46 being journaled to suitably enclose the bevel-gears 44, 45 within a housing 48 secured beneath the cloth-plate. The construction thus far described comprises 90 one well known form of hemstitching machine and the several parts thereof cooperate in the usual manner in the formation of hemstitches. 95

Referring now more particularly to the subject of this invention, a needle-guard 49 is provided intermediate its ends with a hub 50 fulcrumed upon a pivot-screw 51 eccentrically journaled in a lug 52 provided on a plate 53 suitably secured upon the housing 48 by means of screws, as 54. The eccentric-stud or pivot-screw 51 is secured in adjusted position by means of a set-screw 55. The lower end of the needle-guard 49 is connected by means of a pitman 56 and strap 57 within an eccentric 58 suitably secured upon the lower end of the loop-taker shaft 46, whereby the upper end of the needle-guard is caused to approach and recede from the loop-taker through a suitable cut away portion in the feed-dog 35. The operative face of the needle-guard is notched centrally thereof to a depth indicated by the dotted line 59, in order to insure its action upon the needle 17. 110

Referring now more particularly to Figs. 4, 5 and 6 the throat-plate 37 is shown as provided with the usual elongated needle-aperture 60 permitting lateral movements therein of the needle 17 transversely of the direction of feed, and the dot-dash line $x-y$ represents the loop-taking position of the loop-taker beak. Fig. 4 shows the needle in the position it occupies immediately after penetrating the material off the hem- 115 120 125

fold and just preceding the beginning of its fabric-thread drawing movement to the right. The position of the needle-guard 49 in Fig. 4 indicates that it is out of the way of the needle 17 and in fact sufficiently so to permit a small adjustment of the lateral throw of the needle. As the needle now commences to move to the right while continuing its descent, there is a marked tendency to spring the needle by its action on the fabric-threads, as well as a tendency to, by reason of inertia, throw out the needle-thread on the left hand side of the needle. In order to overcome both of these tendencies, the needle-guard 49 is caused to follow the needle at a greater rate of speed than that of the laterally moving needle 17. Fig. 5 shows the needle in its lowest position wherein it has completed approximately a half of its lateral movement. It will be observed that the needle-guard is now very close to the needle. The needle now begins its ascent while continuing its lateral movement until it reaches the loop-taking position illustrated in Fig. 6. The needle-guard 49 is now close to the needle and insures this position in spite of deflection in the opposite direction from that of its lateral movement. It is of course to be understood that when the needle penetrates the material on the hem-fold, i. e., without lateral movement, the needle-guard likewise is in position to back up the needle and its thread to cause the needle-thread loop to be thrown out to the right, or in the direction of the loop-taker.

In case it is desired to alter the position of the needle-guard at loop-taking position, it is only necessary to adjust the eccentric stud 51.

Having thus set forth the nature of the invention, what I claim herein is—

1. In a sewing machine, in combination, a needle, means for imparting endwise reciprocating movements to said needle, a loop-taker complementary to the needle in the formation of stitches, means for imparting lateral movements to the needle in and relatively to the material being stitched, a needle-guard, and means for actuating said needle-guard in timed relation with respect to said lateral movements of the needle to insure in successive stitches a substantially constant relative position of the needle

and loop-taker at the time of seizure of the needle-thread loop by said loop-taker.

2. In a sewing machine, the combination with stitch-forming mechanism including a needle and complementary loop-taking means, feeding mechanism, and means for imparting lateral movements to the needle in a direction substantially transverse to the line of seam-formation, of a needle-guard, and means for actuating said needle-guard in timed relation with respect to said lateral movements of the needle to insure in successive stitches a substantially constant position of the needle and loop-taking means at the time of seizure of the needle-thread loop.

3. In a hemstitching machine, the combination with a needle and a loop-taker having a substantially constant position at the time of seizure of the needle-thread loops, and means for imparting work penetrating and thread-drawing movements to said needle, of a needle-guard retracted out of the way of the needle during the work-penetrating movements of the latter, and means for actuating said needle-guard at a greater rate of speed than the rate of lateral movement of the needle to correct inadvertent deflections of the needle.

4. In a sewing machine, the combination with stitch-forming mechanism including a needle and a complementary loop-taker, of a vibratory needle-guard, a fulcrum for said needle-guard, means for oscillating said needle-guard upon said fulcrum, and means permitting adjustment of the fulcrum of said needle-guard to vary the position of the latter in a plane of the needle-path of movement whereby to determine the position of the needle-point with respect to the loop-taker.

5. In a sewing machine, in combination, a needle, a loop-taker, means for vertically reciprocating said needle, feeding mechanism, means for laterally vibrating the needle toward and from said loop-taker in a direction substantially transverse to the line of seam-formation, a guard-device, and means for actuating said guard-device to back up the needle during its lateral movements toward the loop-taker.

In testimony whereof, I have signed my name to this specification.

JOHN C. RINGE.
